ADJUSTABLE DISPLACEMENT METER OR
PUMP

Robert T. Knapp, Pasadena, Calif., assignor of thirty-three and one-third per cent to Rudolph A. Rieck and thirty-three and one-third per cent to Forest O. Rieck, both of Los Angeles, Calif.

Application October 12, 1937, Serial No. 163,603

12 Claims. (Cl. 103—139)

This invention relates to positive fluid displacement rotary machines and pertains particularly to a metering type of fluid displacement rotary machine of the laterally reciprocating vane form, provided with means for varying the volumetric capacity thereof per revolution through a narrow range to adjust the machine for accurate metering use.

The invention is particularly directed to that type of rotary machine which embodies a rotor member mounted within a concentric rotor chamber or stator provided with coaxially shaped end walls disposed at the opposite axial ends of said rotor and defining vane-guiding cams, and vane members mounted on said rotor and extending transversely with respect to a plane of rotation thereof in engagement with both of said guiding cams, said vane members being slidably mounted on said rotor for laterally reciprocating motion, that is, for motion in a direction transverse to a plane of rotation of the rotor. The invention is applicable in general to the structures described in my issued Patent No. 2,020,611 and in my copending applications Serial Nos. 123,237 and 135,246, filed January 30, 1937, and April 6, 1937, respectively, as well as to structures embodying rectangular vanes, instead of trapezoidal vanes as specifically described in my above-mentioned patent and patent applications.

The vane members are carried within suitable slots in the rotor member, and one of the important objects of the invention is to provide secondary displacement or pump means within such slots, together with means for varying the displacement thereof to provide for minor variations in the volumetric capacity of the rotary machine per revolution.

A further object of the invention is to provide a variable capacity, positive fluid displacement rotary machine adapted primarily for metering purposes, which may be employed in the role of a metering pump device adapted for operation at relatively high capacities and pressures, which will discharge a measured quantity of fluid per revolution, and which is readily adjustable within a sufficient range to provide for accurate metering of different types of fluid or under different operating conditions.

It will readily be appreciated that any fluid metering device is required to be adjustable within a minor range so that accurate metering of any particular fluid under a particular set of operating conditions may be established. This is particularly true in view of the fact that it is commercially impossible to produce meters or

comparable mechanical devices which are so accurately machined that they will have a prescribed volumetric capacity per revolution, in view of manufacturing tolerances which are necessary. Furthermore, due to the differences in compressibility of various liquids, it is frequently necessary to adjust a metering device whenever there is change in operating pressures or where the device is used on a different liquid from that for which it was originally adjusted.

Other objects of the invention will be brought out in the ensuing description of certain embodiments thereof, or will be apparent from such description. The accompanying drawings illustrate such embodiments and referring thereto:

Fig. 1 is a longitudinal section of a device according to the present invention, showing the construction of a form of stator portion which may be employed for the device;

Figs. 2, 3, and 4 represent the two cam plates 20 and the rotor assembly, the rotor assembly being shown in plan view and the cam plates being turned outwardly therefrom and shown in correlated perspective;

Fig. 5 is a longitudinal section of a rotor member embodying the present invention, adapted to be incorporated in the rotary machine shown in Fig. 1;

Fig. 6 is a transverse partly sectional view thereof, taken on line 6—6 in Fig. 5;

Fig. 7 is a transverse section taken on line 7—7 in Fig. 5;

Fig. 8 is a view corresponding to Fig. 5, showing an alternative embodiment of the invention;

Fig. 9 is a view corresponding to Figs. 5 and 8, showing a further embodiment of the invention;

Fig. 10 is a fragmentary transverse section thereof, taken on line 10—10 in Fig. 9;

Fig. 11 is a transverse section of a metering machine according to the present invention, embodying a further modification of the device;

Fig. 12 is a longitudinal section of the form of device shown in Fig. 11, taken on line 12—12 therein;

Fig. 13 is a large scale face view of one of the vane members employed in the present device, showing the manner in which a variation of the slot capacity operates to vary the volumetric capacity of the machine per revolution;

Fig. 14 is a view corresponding generally to Fig. 13, illustrating the construction and operation of one particular modification of the invention;

Fig. 15 is a partly diagrammatic view corre-

sponding to a transverse section of the form of rotor structure illustrated in Fig. 14; and

Fig. 16 is a partly broken away longitudinal section of a "single-ended" meter structure, in which the variable displacement feature of this invention is incorporated.

Referring particularly to Figs. 1 through 4, the rotary device of the present invention may comprise a rotor 1 mounted on a shaft 2 and disposed within a concentric housing 3 provided with end plates 4 and 5 carrying suitable bearings such as shown at 6 and 7 for support of the shaft 2. The rotor 1 is provided with a plurality of vanes 8 slidably disposed within suitable longitudinal slots 9 in the rotor 1 in such manner as to extend transversely with respect to a plane of rotation of said rotor 1. The respective end plates 4 and 5 each carry a cam plate as shown at 11 and 12. The cams 11 and 12 are circular in shape and serve as vane guiding cams; the faces 11' and 12' of these cams are of such a shape as may be generated by the lateral limits of a plane surface which is rotated about the axis of rotation of the shaft 2, said generating plane being moved longitudinally of the shaft 2 and in its own plane during its rotation about said axis so that one or more complete reciprocations are effected in one rotation of 360°.

As taught in the above-mentioned issued patent and the copending patent applications, the cam faces may advantageously be substantially of such shape as would be generated by the outwardly converging lateral edges of a plane surface of trapezoidal shape rotated about a line parallel to the axis of rotation of the shaft 2 and reciprocated axially. This particular design of the cams is preferably only, and as described in the above-mentioned issued patent the vanes themselves may be of any one of several different shapes, either in the suggested form of symmetrical trapezoid as specifically illustrated herein, or with the edge portions curved concavely or convexly after the manner shown in Figs. 14 and 15 of the above-mentioned issued patent. The principles of the present invention apply equally well to constructions employing any one of the above-described types of vanes, as well as to constructions in which the axial ends of the vanes are parallel with one another. Similarly, the vanes may be so mounted in the rotor member as to have a substantially axial longitudinal movement, as in the specific forms herein delineated, or as to have a longitudinal movement at an angle to the axis of the rotor, as in the form shown in Fig. 13 of Patent No. 2,020,611. Likewise, as in the present described form, the vanes may extend radially outwardly within the rotor, or at an angle to a radius, as shown in Fig. 12 of said issued patent. Furthermore, the invention is applicable to "single-ended" pump structures employing axially reciprocable vane elements, such as shown in United States Reissue Patent No. 19,783, dated December 3, 1935. Combinations of these constructions are also within the contemplation of this invention, as will be apparent to one skilled in the art, and this invention is directed primarily to the construction of the slots in the rotor within which the vane is slidably disposed, providing for the desired variation in the volumetric capacity of the device per revolution.

With the use of trapezoidal shaped vanes according to the preferred forms herein described, the cams 11 and 12 remain substantially invariant with respect to each other so that the cross-

section of the space between them taken upon a plane containing the generating trapezoid is substantially identical in shape with all similarly taken cross-sections, the axial distance between said cams at any given radius being substantially constant circumferentially and equal to the effective axial length of the vanes 8 at that radius. This is not strictly true where constructions such as that described in my copending application Serial No. 135,246 is employed, where the cams are modified in shape to engage the leading and trailing edges of a vane of finite width according to the teachings of that application, but the principles underlying the construction are substantially the same. As will be apparent, the cam faces 11' and 12' provide the desired guiding and sealing faces for the lateral edges 8a and 8b of the vanes 8, and an outer guiding and sealing face 13 is provided on the housing 3 against which the outer or peripheral edges 8c of the vanes 8 may bear. The outer face 13 is preferably cylindrical in shape and may be provided by means of an annulus 14 having a press fit within the housing 3, and the inner diameter of the annulus 14 is preferably only slightly greater than the outer diameter of the rotor 1, so as to provide a minimum clearance between said rotor and the face 13, whereby cross-circulation of fluid between the displacement spaces or chambers of the respective axial ends of the rotor is substantially prevented. The sealing and guiding surfaces 11', 12' and 13 serve to define and enclose a rotor chamber within which the rotor 1 is mounted.

Referring more particularly to Figs. 1 through 4, the rotor 1 is shown as comprising a main body portion 1a of such diameter as to provide a running fit with the surface 13 of the annulus 14, and hub portions 1b of reduced diameter projecting laterally at the respective ends of said body portion. The main body 1a of the rotor is formed as two oppositely disposed truncated cones spaced by an intermediate cylindrical portion which constitutes the outside diameter of the rotor and, as above set forth, fits closely within the annulus 14. The angle which the conical faces make with the axis of the rotor preferably conforms to the angle of inclination of the cam faces 11' and 12' and to the angle which the vane edges 8a and 8b make with the edge 8c as is illustrated in Figs. 1 and 12. This is a structurally preferable but not a necessary feature of the construction, particularly where the device is employed for handling a substantially incompressible fluid. The slots 9 are formed in the body portion and hub portions of the rotor 1, and serve to support the vanes in their desired positions and cause the same to rotate with the rotor, while permitting free reciprocation of the vanes under the influence of the guiding cams. The rotor 1 cooperates with the guiding and sealing surfaces 11', 12' and 13 to define separate displacement chambers at the respective ends of the rotor body portion 1a.

The housing 3 is provided with an inlet 15 and an outlet 16 which communicate respectively with inlet passage 17 and outlet passage 18 arranged along the inner periphery of housing 3 exteriorly of the annulus 14. The respective passages 17 and 18 are provided with portions which extend laterally outwardly of the annulus 14 for communication with certain inlet and discharge ports in the device, as hereinafter described. The cam plates 11 and 12 are provided with one or more inlet ports 19 and 21, respectively, which ports communicate with the above-mentioned laterally

extending portions of the inlet passage 17 (said projecting portions being indicated at 17a and 17b), and with one or more discharge ports 22 and 23, which communicate with the laterally extending portions 18a and 18b, respectively, of the passage 18. Where the cams 11 and 12 are such as to produce but a single reciprocation of the vanes per revolution, the inlet and outlet ports may conveniently be disposed substantially 10 180° apart, as will be apparent to one skilled in the art.

In the present described form of the device, the respective inlet and discharge ports may communicate to the interior of the device, that is, 15 to the fluid displacement chambers at the respective axial sides of the rotor 1, through circumferentially elongated passages in the cam plates, opening through the cam faces 11' and 12', as indicated at 24, 25, 26, and 27, said passages 24 through 27 being preferably inclined in a spiral form so that the lateral edges 8a and 8b of the vanes 8 will be subjected to uniform wear in passing over these passages. The above-described arrangement of ports is given by way of example only, inasmuch as such ports will depend upon the use to which the device is to be put.

From the above description it will be seen that the cam faces 11' and 12' may be formed upon the end plates 4 and 5, but it will also be apparent that where important wear-resisting qualities are desired in the cam faces under particularly severe operating conditions, for example, the structure may alternatively be formed as separate end plates and cam faces, the latter being formed of a wear-resistant material, and the former of a less expensive material. In the actual showings, referring particularly to Figs. 1 to 4, the portions of the device on which the cam faces 11' and 12' are formed comprise separate ring-shaped elements 11 and 12 having inner ends of small diameter such that they may set within the annulus 14, and outer ends of somewhat increased diameter so as to abut against the lateral ends of said annulus 14. The respective end plates 4 and 5 may thus be caused to bear directly against the separate members 11 and 12 which carry the cam faces 11' and 12', firmly holding said members in fixed relation with respect to the housing 3. Suitable dowel members may be provided, as will be apparent to one skilled in the art, whereby the respective cam faces are placed in the desired orientation with respect to one another and with respect to the inlet and outlet passages 17 and 18. The inner diameter of the members 11 and 12 which provide the faces 11' and 12' is preferably such as to have a relatively small clearance with the hub portions 1b of the rotor 1. The enlarged outer ends of the end plates 4 and 5 are preferably recessed as at 20 adjacent the inlet and discharge ports, so that free flow of fluid between said ports and the respective inlet and outlet passages is provided.

In the above description, the casing or housing 3 is set forth as provided with respective inlet or outlet passage means such as shown at 16 through 18. It will be realized that the respective passages may be reversed in function so that the inlet 16 serves as an outlet, depending upon the direction of rotation of the shaft or rotor 1. I have, however, illustrated for convenience in description a specific direction of rotation by arrows in Figs. 1, 3, 6, 11, and 12.

While the specific design of the cam faces 11'

and 12' is not of particular moment in connection with the present disclosed features of the device, and is obviously subject to wide variation, it may be said that in one common form these cam faces may roughly be divided into 90° quadrants, as may be visualized from Figs. 2 and 4 (these quadrants actually depart from 90° in the actual construction, as set forth in Serial No. 135,246, for certain reasons which are not pertinent hereto). Referring more particularly to Fig. 2, for the purpose of description, these quadrants may be visualized as extending respectively between the four points indicated at A, B, C, and D. The quadrant A-B will illustrate an inlet quadrant for the displacement chamber defined between the cam face 11' and the adjacent inclined face or side wall of the rotor 1 (assuming the delineated direction of rotation). The axial separation between the cam face 11' and the adjacent inclined face of the rotor thus increases from the point A to the point B, and the incoming fluid will flow freely into the displacement chambers defined between the vanes E and F (see Fig. 3) through the slot 24. The vane F is in sealing engagement with the surface between the points B and C, and the pressure of the incoming fluid will be applied against the exposed face of said vane, causing a rotation of the rotor. The displacement chamber between the vane E and the point A will also be filled with the incoming fluid, and when the vane E reaches the point B, sealing off the end of the slot 24, the fluid pressure will be applied to the vane E, and the vane F will have reached the point C, whereupon the fluid between the vanes E and F will start to discharge from the device through the slot 26. The quadrant C-D is reversed in slope to the quadrant A-B, and the axial separation of the face 11' from the rotor gradually diminishes to the clearance value at the point D. The discharge of fluid from the displacement chamber between the vanes E and F continues until the vane E has reached the point D, at which time the vane F is substantially in position to pass the point A, whereupon the volume of the space between the vanes E and F will again begin to increase and allow inflow of a further quantity of fluid. It will be appreciated that the same operations as above described will take place between each pair of vanes, during rotation of the device, and that the operation of the opposite end of the device is entirely comparable, the fluid flowing into the right hand side of the device through the slot 25, and discharged through the slot 27.

Suitable passages 35 are provided in the hub portion 1b of the rotor 1, preferably at positions closely adjacent the intersection of the conical side walls of the body portion 1a or the rotor with said hub portion 1b, said passages opening at their outer ends through the periphery of the respective hub portions and communicating at their inner ends with the slots 9 inwardly of the vanes 8. The passages 35 are provided at each side or end of the rotor body 1a (in a double-ended construction), and may be disposed adjacent the entering or leading face of the respective vanes, so as to place the respective end portions of a particular slot 9 in fluid communication with the fluid displacement chamber which is in advance of the position of a particular vane so that the volumetric capacity of the respective ends of the slot is included in the volumetric capacity of the respective adjacent displacement chamber. The passages 35 may alternatively be

disposed adjacent the trailing face of the vanes, if desired, with equal results. In general, I find it desirable to be consistent in the placement thereof, so that all the passages will be adjacent either the entering or trailing face of each blade or vane.

As an alternative to the provision of passages 35 in the rotor itself, I may provide cut-away corner portions for the vanes, as shown at 60 10 in Figs. 10 and 12 in the aforementioned copending application Serial No. 123,237, or provide passages within the vane structure, as shown at 15 13 in Fig. 13 in said application.

In view of the fact that during rotation the 15 vanes will be forced outwardly against the surfaces 11', 12', and 13, thus providing a clearance between the inner edge 8d of the vane and the bottom of the slot 9 on the assumption that the bottom of the slot 9 remains in fixed position during 20 operation, the pressure difference at opposite sides of the rotor 1 will have a tendency to be neutralized through the slot 9 and I provide a member 42 at said inner edge of the vane, in engagement with the bottom of the slot 9, to prevent 25 cross-circulation and cooperate with the capacity-variation means hereinafter described. The member 42 is conveniently disposed within a suitable outwardly extending notch 41 formed in the vane body and is of such thickness as to have a minimum side clearance within the slot 9. The member 42 is preferably maintained in place within and in engagement with the bottom of the slot 9 through the agency of one or more spring members 43 positioned to bear against the outer 30 edge of the member 42 and against the inner edge of the slot 41 in order to overcome the effect of centrifugal force. Suitable guide pins or the like may be provided as at 44 for the purpose of maintaining the springs 43 in their desired position.

For the purpose of providing an outward pressure against the central portion of the inward edge of the vanes 8 to counterbalance the radially inward pressure on the central portion of the outward edge 8c of said vanes, and for producing a radially inward pressure on the member 42 against the bottom of the slot 9 and to oppose any outward pressure which may be communicated thereto through the slot 9 beneath the edge 8d of the vanes from one side or the other, I may provide means for applying the same pressure to the space between the outer edge of the member 42 and the outer edge of the notch 41 as is present at the periphery of the body portion 1a of the rotor 1. For this purpose I may provide a passage 45 within the rotor extending from the periphery of said rotor body portion and communicating with the aforesaid space. The position of the passages 45 with respect to the rotor 45 and the vanes is clearly shown in Figs. 1, 3, and 13, wherein it will be seen that the passages open at the periphery of the rotor at the medial plane of the rotor. It will be appreciated that this position of the passage corresponds to the average pressure between the displacement chambers at the opposite sides of the rotor, which is preferable for the proper operation of the device where the counterbalancing passage is provided in the rotor. The provision of passage means 45 as 65 above described is considered desirable only where the device is to be operated in the role of a "metering" pump, where significant differences in pressure exist between the inlet and outlet. In conventional meter operation, the device will operate as a motor at low pressure differentials,

wherefore such pressure counterbalancing means are superfluous.

Each slot 9 is of sufficient length to accommodate the movement of the corresponding vane 8 through its entire stroke from one side to the other, even though the vane undergoes considerable outward movement due to wear on the edges 8a, 8b, and 8c. The cam plates 11 and 12 overlap the end portions of these slots to varying degrees at one or both ends (according to the 10 rotative position of any particular slot with respect to the cam faces). The clearance spaces thus formed at the ends of the slots (as shown for example at 9a in Fig. 13) will expand or contract, dependent upon whether the vane is moving away from or toward the respective end wall of the particular slot. It will be observed that in the construction herein shown the passages 35 permit free interflow of fluid between the displacement chambers and the aforesaid clearance 20 spaces at a position inwardly of the inward edge 8d of the vanes 8, thus eliminating the trapping of fluid in these spaces and thereby eliminating mechanical drag on the device from this source, without detracting from the volumetric efficiency 25 thereof.

According to the present invention the desired adjustment of the volumetric capacity of the device is secured through a quantitative control of the interflow of fluid between the displacement chambers and the aforesaid clearance spaces, as by the provision of means for forcing a greater or lesser quantity of fluid from such clearance spaces into the associated displacement chamber, whereby a controlled contribution to the effective volumetric capacity of the principal displacement chambers by certain secondary displacement chambers provided by means of said clearance spaces, is obtained. In effect, a small secondary reciprocating pump is established within 30 each of such clearance spaces, and the desired quantitative control of the pumping action of these secondary pumps with reference to the associated displacement chambers is secured by varying the displacement of such secondary 35 pumps. The variation in the displacement of these secondary pumps is obtained in the present construction by the novel provision of means for varying the effective area of the pumping members in such clearance spaces while leaving the stroke thereof at a constant value, instead of the customary provision of means for varying the pumping stroke, as employed in the conventional variable displacement reciprocating pump.

The desired adjustment of the volumetric capacity of the device per revolution may be obtained by varying the effective depth of one or more of the slots 9. Referring particularly to Fig. 13, a vane 8 is shown at its ultimate left-hand position, and as the vane moves toward the right in the direction of the arrow R the space 9a at the right-hand end of the slot 9 becomes, in effect, a small displacement chamber with the portion of the vane from the inner edge 8d to the outer edge of the slot plus the portion of the member 42 (which functions as a piston, and will be hereinafter referred to as a "piston member") from the bottom of the slot to said inner edge of the vane constituting a piston head which will force a portion of the fluid entrapped within the space 9a outwardly thereof through the passage 35'. In this particular figure, the vane has just passed to its left-hand position so that the left-hand end of the vane plus the left-hand exposed end of the piston member 42 has forced the maxi- 70 75

mum amount of fluid out of the left-hand end $8a$ of the slot 8 into the space 46 in advance of said vane. At this position, the space 46 is at its maximum volume, at the termination of an "intake" 5 movement of the device at its left side, and the total volume of the fluid under treatment is that of the space 46 plus that of the end of the slot 8 . As that particular portion of the device is moved around the device to cause a discharge of the 10 fluid, the vane will move in the direction of the arrow R , increasing the volume of the space $8a$ at the left end of the slot, and thus causing a decrease in the amount of fluid which would be discharged from the device through the discharge 15 ports. It will be seen that where it is desired to increase the capacity of the device, it is merely necessary to decrease the depth of the slot 8 , so that less fluid will be drawn into the slot space 20 $8a$ during the discharge of fluid from the corresponding displacement chamber, and, similarly, when it is desired to slightly decrease the capacity of the device, it is merely necessary to increase the depth of the slot. The springs 43 serve 25 to keep the piston member 42 in contact with the bottom of the slot 8 , as above brought out, and the members 42 are preferably made of somewhat greater outward length than the maximum depth of the slots, so that the desired pumping action will be maintained at the maximum inward position of the bottom of the slot, even though the vanes should wear to the extent that the inner edges $8d$ thereof practically reach the outer edges of the slots.

Inasmuch as the effective area of the pumping 35 piston operating in each clearance space is made up of the area of the end of that portion of the vane which projects inwardly of the slot plus the area of the exposed or inwardly projecting portion of the end of the member 42 which moves 40 with such vane, such effective area will remain constant (with one "setting" of the device) independent of the wear of the vanes and the consequent outward movement thereof, for the simple reason that as the piston effect of the vane decreases, the piston effect of the member 42 increases and therefore the proportion of the effective area provided by each element is im- 45 material.

An alternative method of securing the desired 50 adjustment is illustrated in Fig. 14, in which the rotor member is provided with a slot $8'$ of fixed depth, and the desired adjustment in the effective pumping action is secured through the agency 55 of a modified form of piston member $42'$ slidably disposed within a suitable notch $41'$ in a vane $8'$, said piston member being biased inwardly by means of a spring member $43'$ against a sealing member 48 threadedly secured within a co- 60 actingly threaded bore 49 in the rotor body $1b$. The sealing member 48 is provided with an outwardly directed sealing portion $48a$ adapted to bear against the bottom or inner surface 58 of the piston member $42'$. The member $42'$ is of such thickness (in a circumferential direction) 65 as to fit closely within the slot $8'$, preventing cross-circulation of fluid within the slot as far inwardly as the surface 58 , and the sealing portion $48a$ of the member 48 is of a diameter equal to or greater than the diameter of the slot, preventing cross-circulation of fluid from the 70 surface 58 to the bottom of the slot. The operation of this form of the invention is entirely comparable to the form shown in Fig. 13, the portion of the vane $8'$ and the projecting portion of the member $42'$ between the outer edge of the slot $8'$

and the surface 58 constituting a piston head which will force a portion of the fluid entrapped within the ends of the slot $8'$ outwardly into the adjacent displacement chamber through one of the respective openings 35 . Inward and outward 5 adjustment of the member 48 will effect a corresponding movement of the member $42'$ as between the positions indicated, varying the effective piston area between such values as are indicated at p_1 and p_2 . 10

It will be appreciated that the member 48 actually defines the "bottom" or effective inner limit of the slot 8 , as far as the size of the small pumping chambers is concerned, inasmuch as the portions of the slot inwardly of the position of 15 the sealing surface 58 of the member $42'$ are wholly without function.

The desired inward and outward adjustment of the member 48 may advantageously be secured by employing an odd number of vanes, five, for 20 example, disposed as indicated at L, M, N, O, and P in Fig. 15, and extending the threaded bore 49 diametrically through the rotor as indicated at L', M', N', O', and P'. In order to effect an adjustment of the position of the member 48 without necessitating a disassembly of the device, a suitable opening $49'$ may be provided in the annulus 14 at one point in the periphery thereof, in alignment with the bore 49 , and another suitable opening $49''$ may be provided in the casing 3 in 30 alignment with the opening $49'$. The opening $49''$ may be provided with a threaded plug member, not shown, which may be removed when it is desired to adjust the device, the rotor being rotated so that a particular bore 49 is in alignment 35 with the bores $49'$ and $49''$, a long-shanked screw-driver being inserted in the aligned openings into engagement with a screw slot in the inner end of the member 48 , for rotation of the member 48 in the direction which will provide the desired 40 adjustment.

In the form of invention shown in Figs. 5, 6, and 7, the capacity adjustment is secured through an inward and outward movement of the bottom of the slot 8 within which the vanes 8 reciprocate, through the agency of movable follower members 51 defining the bottom or inner surfaces of such slots and comprising sealing members corresponding in function to the sealing members 48 above. The sealing follower 45 members 51 may be provided with sloping inner faces at the respective ends thereof, as at 52 and 53 , and suitable supporting or spacing means are provided in engagement with such sloping portions in order to secure the desired outward spacing of the followers 51 with respect to the axis 50 of rotation of the device. According to this particular form of the invention such spacing means is provided by two opposed spider elements 54 55 threadedly mounted on a right and left-hand co-actingly threaded screw member 55 mounted for rotation along the axis of the rotor member and positioned against axial movement through the agency of a suitable lock screw 56 . The member 55 preferably extends through a suitable axial bore 57 in the shaft 2 in position for external access, as by means of a screw-driver or the like which may be brought into engagement with a screw slot 58 in the end of said member. In order to facilitate assembly, the rotor may be 60 formed as three separate elements intersecured through the agency of suitable bolt means, such as a driving shaft end 59 , a rotor body portion 61 constituting the hub portion $1a$ and the principal proportion of the hub portion $1b$, and a 65 70 75

stub shaft end 62, the several parts being inter-secured through the agency of a plurality of screws 63. A suitable gear or the like may be provided on a convenient portion of the shaft 2, as at 64, for association of the device with a suitable counting element or the like such as shown at 65 in Fig. 1.

The form of device shown in Fig. 8 is comparable to that shown in Figs. 5 to 7, with the exception that the followers 66, corresponding in function to the sealing follower members 51 above, are provided with an inner surface tapering in one direction along the axis of rotation of the device and an axially movable conical 10 spacing member 67 is provided in place of the spiders 64. The conical spacing member 67 is conveniently mounted on an axially disposed pin member 68 threadedly mounted within the shaft portion 69. This form of device may also be 15 formed as three separate sections 71, 72, and 73, the respective end members 71 and 73 being secured to the central or hub member 72 through the agency of short screws extending inwardly from each end of the rotor as shown at 74.

The form of invention shown in Figs. 9 and 10 provides the inward and outward spacing of the bottom of the slots 8 by means of sealing follower members 81 slidably disposed for inward and outward movement within the slot 8 and provided with inwardly directed pin members adjacent the respective ends thereof as at 82 and 83, the inner ends of which are in engagement with an axially movable adjustment member 84 provided with two conical adjustment surfaces 85 and 86 adapted to engage the inner ends of said pins 82 and 83 to move the followers 81 inwardly or outwardly upon axial movement of the member 84 such as may be attained by rotation of a threaded shaft portion 87 threadedly disposed within the shaft 2.

In each of the forms described in Figs. 5 through 10 the inward movement of the followers 51, 66, and 81 is caused by the compression springs 43 which bear inwardly against the sealing member 42 which in turn bears inwardly against the outer edge or face of the follower. It will be appreciated that where the device is to be used at excessively high speeds it may be desirable to provide relatively strong spring structures at 43 in order to overcome or counterbalance the tendency for the sealing member and the follower member to move outwardly under the influence of the rotative motion thereof, which may result in some cases in producing a 45 rather high outward pressure of the vanes 8 against the annular surface 13. In order to relieve the device of the outward thrust of the follower member due to centrifugal action, I may employ a construction of the type shown in Figs. 50 11 and 12 in which a plurality of sealing or follower members 91 slidably disposed within the respective slots 8 are threadedly secured to a rotatable hub 92 located interiorly of the main rotor body and provided with coacting spiral 55 threads 93 adapted to cause inward and outward movement of the sealing or follower members 91 upon relative rotation of the hub 92 with respect to the main body of the rotor in one direction or the other. This construction is entirely 60 comparable to the conventional form of "Universal" chuck such as employed on lathes and drill presses, and any suitable means for securing the desired relative rotation of the hub portion 92 with respect to the main rotor body may 65 be provided, as through the agency of a spur 70 75

gear 92' secured to said hub 92 and adapted for engagement by a suitable removable key 94 which may extend through a suitable opening 95 in the hub member upon alignment thereof with a suitable opening 96 in an end wall 4a of the casting 3. A suitable plug may be provided as shown in dot-dash lines at 97 whereby the opening 96 may be kept closed during operation of the device.

It will be appreciated that the amount of inward and outward adjustment which is required 10 for the regulation of the depth of a vane-carrying slot in the rotor is dependent wholly upon the particular operating requirements of the device. Where relatively narrow slots and vanes are 15 employed (as measured in a circumferential direction) it may be necessary to provide for a relatively large inward and outward adjustment of the bottom of the slots in order to obtain an adequate variation in the capacity of the device, and where relatively thick vanes and wide slots are 20 employed, it may only be necessary to provide a minor variation in the whole number of slots, or, as an alternative, a major variation in but one of the slots. Similarly, a device provided with four vanes, for example, may have three thin 25 vanes and one thick vane, the bottoms of the slots carrying the thin vanes being fixed and the bottom of the slot carrying the thick vane being adjustable.

In general, where the device is to be employed 30 purely as a metering means, there will be little difference in the inlet and outlet pressures, and the only work which the device will have to perform is that of overcoming the friction of the parts, including the associated counting element. 35 For this reason the parts may be made relatively light in construction. The device may advantageously be employed as a metering pump, or the like, by appropriately increasing the strength of the parts, dependent upon the operating conditions to be encountered. It will be appreciated 40 that the proportions of the parts shown are illustrative only, and while a rather heavy shaft and bearing structure is shown in Figs. 1 through 10 and 16, such a construction is necessary only 45 where the device is to be employed as a metering pump, inasmuch as where the device is employed simply as a meter, the strength of the shaft need be only such as to drive the associated counting or registering mechanism.

While the invention as described is directed primarily to the rotary machine as a whole, it will be appreciated that the construction of the housing portion of the device is quite equivalent to the structures described and claimed in the 50 above-mentioned patent and patent applications, the principal differences in the present construction residing in the construction of the rotor member per se. The rotor member is subject to sale as a separate unit, either alone or in association with appropriate vane members, and for this reason is separately claimed herein.

Numerous modifications of the device, within the spirit and contemplation of the invention, will suggest themselves to those skilled in the art, 55 and I do not choose to be restricted to the specific forms herein delineated and described, but rather to the scope of the subjoined claims. For example, I have herein shown and described but two forms of piston member which may be employed to cooperate with the sealing member at the inner limit of the slots and seal the respective slots against cross-circulation of fluid, but it will be appreciated that any desired type of piston means which will move along the slot with

the blade or vane member will have the desired pumping or piston action within the slot, and will serve to force fluid into and out of the adjacent displacement chambers.

As mentioned above, the present invention is adapted to incorporation in structures such as shown in United States Reissue Patent No. 19,783 to Roberts, dated December 3, 1935, and such an adaptation is shown in Fig. 16. Referring to this figure, a housing is indicated at 101, provided with bearings 102 and 103 carrying a rotor 104, said rotor being provided with a plurality of radial slots 105 and an axially movable vane 106 in each slot. In the particular form shown, the left-hand end wall 107 of the casing 101 is provided with a cam surface adapted to effect a longitudinal reciprocation of the vanes 106 upon rotation of the rotor 104 with respect to the casing. Suitable spring members 108 are provided at the opposite axial ends of the vanes to cause the same to persist in engagement with the cam surface, performing the function of the opposed cam member shown in the other forms of the device, a suitable radial extension 109 of the rotor 104 being provided against which the rearward ends of the springs 108 may bear. Intercommunication of the rearward ends of each of the slots 105 is provided, in order to prevent a hydrostatic trap upon axial movement of the respective vanes, as by cutting the rotor away adjacent the outer rearward edge thereof, as shown at 110. A sealing member 111, corresponding in function and position to the sealing members 42 above, is provided for each of the vanes 106, in position to bear against the upper surface of a follower 112 which is adapted for radial movement inwardly and outwardly of the hub portion of the rotor 104 through the agency of any suitable actuating means such as an axially movable conical spacing member 113 corresponding in position and function to the member 67 shown in Fig. 8. A suitable passage 114 is provided in the hub portion of the rotor adjacent the position of each of the vanes 106 and providing fluid communication between the forward ends of the slots 105 and the space between the rotor and the cam face 107, corresponding in function to the passages 35 above. Suitable inlet and discharge ports will be provided in the cam face 107, as will be apparent to those skilled in the art.

In the subjoined claims the expressions "inward" and "outward" are employed to designate portions of the structure which are directed "towards" and "away from" the axis of the rotor member, respectively. In the specific delineations of structure herein made, such "inward" and "outward" portions of the device may be considered as "radially inward" and "radially outward" portions, but as brought out hereinbefore, it is not essential that the vanes, for example, extend in a truly radial direction.

I claim:

1. In a rotary machine of the laterally sliding vane type, a rotor construction which comprises: a hub member provided with a plurality of circumferentially spaced slots extending transversely with respect to a plane of rotation of said rotor and each adapted to receive a vane member provided with an inwardly directed piston member of the same effective width as said slot; an inwardly and outwardly movable sealing member disposed within one of said slots and extending across the width thereof in position to engage the inward edge of said piston member; and

means for positioning said sealing member with respect to its outward position within said slot.

2. A rotary machine which comprises: a housing provided with a rotor chamber having fluid inlet and fluid outlet passages and an annular sealing and guiding surface; a rotor concentrically mounted within said chamber and having a peripheral portion closely spaced from said annular surface, and provided with a plurality of circumferentially spaced slots extending transversely with respect to a plane of rotation thereof; a plurality of laterally reciprocable vanes disposed within the respective slots, constrained to rotate with said rotor, and having their outward edges in sealing engagement with said annular surface; a guiding and sealing cam member mounted on said housing at one axial side of said rotor in position to engage the adjacent lateral ends of said vanes; means engaging the opposite lateral ends of said vanes to maintain said vanes in engagement with said guiding and sealing cam member, said cam member and said last-named means cooperating to effect lateral reciprocation of said vanes within said slots upon rotation of said rotor; a piston member extending within each of said slots adjacent the inner edge of the respective vane, said piston member being slidably movable with respect to said vane in a direction transverse to the direction of lateral reciprocation of said vane and constrained to move with said vane during the reciprocating movement thereof; means biasing said piston member toward the bottom of said slot; means for varying the effective working area of said piston member and including sealing means adapted to engage the inwardly directed surface of said piston member and limit the extent to which said piston member projects inwardly of the respective slot and to cooperate with said piston member to provide a seal across said slot and define a displacement chamber at the end of said slot which is adjacent said cam member; and passage means establishing fluid communication between said displacement chamber and said rotor chamber at said one axial side of said rotor.

3. A rotary machine which comprises: a housing provided with a rotor chamber having fluid inlet and fluid outlet passages and an annular sealing and guiding surface; a rotor concentrically mounted within said chamber and having a peripheral portion closely spaced from said annular surface, and provided with a plurality of circumferentially spaced slots extending transversely with respect to a plane of rotation thereof and in fluid communication with said chamber; a plurality of laterally reciprocable vanes disposed within the respective slots, constrained to rotate with said rotor, and having their outward edges in sealing engagement with said annular surface; two opposed guiding and sealing cam members mounted on said housing at the respective axial sides of said rotor and adapted to engage the respective lateral ends of said vanes and effect lateral reciprocation thereof upon rotation of said rotor; a piston member extending within each of said slots adjacent the inner edge of the respective vane and cooperating with said vane and the walls of said slot to establish a fluid seal intermediate the ends of said slot, said piston member being adapted to move with the respective vanes in the lateral reciprocation thereof and movable with respect to the respective vane inwardly and outwardly of said slot; means biasing said piston member inwardly of said slot; and adjustable sealing means within said slot

and extending outwardly into sealing engagement with the inner surface of said piston member for varying the extent of penetration of said piston member inwardly of the respective slot.

5. A rotary machine which comprises: a housing provided with a rotor chamber having fluid inlet and fluid outlet passages and an annular sealing and guiding surface; a rotor concentrically mounted within said chamber and having a peripheral portion closely spaced from said annular surface, and provided with a plurality of circumferentially spaced slots extending transversely with respect to a plane of rotation thereof and in fluid communication with said chamber; 10 a plurality of laterally reciprocable vanes disposed within the respective slots, constrained to rotate with said rotor, and having their outward edges in sealing engagement with said annular surface; two opposed guiding and sealing cam 15 members mounted on said housing at the respective axial sides of said rotor and adapted to engage the respective lateral ends of said vanes and effect lateral reciprocation thereof upon rotation of said rotor; an inwardly biased piston member extending within each of said slots adjacent the inner edge of the respective vane and cooperating with said vane and the walls of said slot to establish a fluid seal intermediate the ends of said slot, and constrained to move with said respective vane during the lateral reciprocation thereof; and means for varying the depth of at least one of said slots.

5. A rotary machine which comprises: a housing provided with a rotor chamber having fluid inlet and fluid outlet passages and an annular sealing and guiding surface; a rotor concentrically mounted within said chamber and having a peripheral portion closely spaced from said annular surface, and provided with a plurality of circumferentially spaced slots extending transversely with respect to a plane of rotation thereof; a plurality of laterally reciprocable vanes disposed within the respective slots, constrained to rotate with said rotor, and having their outward edges in sealing engagement with said annular surface; two opposed guiding and sealing cam members mounted on said housing at the respective axial sides of said rotor and adapted to engage the respective lateral ends of said 45 vanes and effect lateral reciprocation thereof upon rotation of said rotor; a piston member secured to each of said vanes at the inner edge thereof and extending within the respective slots at a position intermediate the ends thereof, said vanes being spaced from the bottom of the respective slots at positions laterally removed from said piston members, and said piston members defining two separate displacement chambers within said slots; passage means providing fluid 50 communication between said displacement chambers and said rotor chamber at the respective axial sides of said rotor; and means for varying the effective inward extension of at least one of said piston members within the respective slots.

65. 6. A rotary machine which comprises: a housing provided with a rotor chamber having fluid inlet and fluid outlet passages and an annular sealing and guiding surface; a rotor concentrically mounted within said chamber and having a peripheral portion closely spaced from said annular surface, and provided with a plurality of circumferentially spaced slots extending transversely with respect to a plane of rotation of said rotor and in fluid communication with said chamber; a plurality of laterally reciprocable vanes dis-

posed within the respective slots, constrained to rotate with said rotor, and having their outward edges in sealing engagement with said annular surface; a follower member slidably disposed at the radially inward portion of at least one of said slots, defining the bottom wall thereof and movable inwardly and outwardly therein to provide a variation in the effective depth thereof; adjustable spacing means cooperating with said follower member to position the same to establish said slot at the desired depth; a piston member extending within said one slot adjacent the inner edge of the respective vane and constrained to move therewith, said piston cooperating with said vane, the walls of said slot and said follower member to establish a fluid seal intermediate the ends of said slot; and two opposed guiding and sealing cam members mounted on said housing at the respective axial sides of said rotor and adapted to engage the respective lateral ends of said vanes and effect lateral reciprocation thereof upon rotation of said rotor.

7. The device as set forth in claim 6, each of said slots being provided with a follower member and a piston member, and said adjustable spacing means being adapted to engage each of said follower members for adjustment of the position of the several follower members as a unit.

8. A rotary machine which comprises: a housing provided with a rotor chamber having fluid inlet and fluid outlet passages and an annular sealing and guiding surface; a rotor concentrically mounted within said chamber and having a peripheral portion closely spaced from said annular surface, and provided with a plurality of circumferentially spaced slots extending transversely with respect to a plane of rotation of said rotor and in fluid communication with said chamber; a plurality of laterally reciprocable vanes disposed within the respective slots, constrained to rotate with said rotor, and having their outward edges in sealing engagement with said annular surface; cam means engaging the respective lateral ends of said vanes and adapted to effect lateral reciprocation thereof upon rotation of said rotor; a piston member secured to each of said vanes at the inner edge thereof and constrained to lateral reciprocating movement with said vanes, said sealing members extending within the respective slots at a position intermediate the ends thereof and movable with reference to the respective vanes in a direction transverse to the lateral reciprocating movement of said vanes; means biasing said piston members inwardly of the respective slots toward engagement with the inner surface of said slots; a sealing member extending within one of said slots and in engagement with the inner edge of the corresponding piston member, said sealing member cooperating with the walls of said slot and the inner edge of said piston member to define two separate displacement chambers within said slot at the respective ends of said slot, and said sealing member being adapted for movement inwardly and outwardly of said slot to determine the extent to which said piston member extends within said slot; and passage means providing fluid communication between said displacement chambers and said rotor chamber.

9. A rotary machine which comprises: a housing provided with a rotor chamber having fluid inlet and fluid outlet passages and an annular sealing and guiding surface; a rotor concentrically mounted within said chamber and having a peripheral portion closely spaced from said

- annular surface, and provided with a plurality of circumferentially spaced slots extending transversely with respect to a plane of rotation thereof; a plurality of laterally reciprocable vanes disposed within the respective slots, constrained to rotate with said rotor, and having their outward edges in sealing engagement with said annular surface; a guiding and sealing cam member mounted on said housing at one axial side of said rotor in position to engage the adjacent lateral ends of said vanes; means engaging the opposite lateral ends of said vanes to maintain said vanes in engagement with said guiding and sealing cam member, said cam member and said last-named means cooperating to effect lateral reciprocation of said vanes within said slots upon rotation of said rotor; a piston member extending within each of said slots adjacent the inner edge of the respective vane, said piston member being slidably movable with respect to said vane in a direction transverse to the direction of lateral reciprocation of said vane and constrained to move with said vane during the reciprocating movement thereof; means biasing said piston member toward the bottom of said slot; sealing means adapted to engage the inwardly directed surface of said piston member to cooperate with said piston member to provide a seal across said slot and define a displacement chamber at the end of said slot which is adjacent said cam member, said slots being open to communication with one another at the side of said piston member away from said cam member; and passage means establishing fluid communication between said displacement chamber and said rotor chamber at said one axial side of said rotor. 10
11. A rotor for use in a rotary machine of the sliding vane type, which comprises: a hub member provided with a plurality of circumferentially spaced slots extending transversely with respect to a plane of rotation of said rotor and each adapted to receive a vane member provided with an inwardly directed piston member having an effective width in a circumferential direction equal to the width of said slot; an inwardly and outwardly movable sealing member disposed within one of said slots, extending across the width thereof in sealing relation to the side walls of said slot, and in position to engage the inward edge of said piston member; and means for positioning said sealing member with respect to its outward position within said slot. 15
12. The construction set forth in claim 11, in which a sealing member is provided in each of said plurality of slots, and in which said last-named means comprises means for coincidentally positioning all of said sealing members as a unit. 20
